MARKING MACHINE

Joseph Weimont, Bogota, N. J., assignor to A. Kimball Company, New York, N. Y., a corporation of New York

Application August 28, 1940, Serial No. 354,466

4 Claims. (Cl. 93—89)

This invention relates to marking machines. In Marsh application, Serial No. 354,481, filed of even date herewith, a pin ticket roll is described which comprises an elongated strip formed of a large number of individual tickets. In such strips the wire staples are passed loosely through the individual tickets without clinching the same to the tickets as is the usual practice. Since the staples are merely loosely hung in the tickets, the legs or pins of the staples may be readily swung to a position substantially parallel to the plane of the ticket, so that the strip may be wound into a flat roll, the successive convolutions of which are closely spaced.

It is desirable, however, in most cases, that the staples be clinched to the ticket before attaching the ticket to the merchandise. It is an object of the present invention to provide a marking machine having a mechanism, operating in cooperation with the feeding and printing mechanisms of such machines, to clinch such loosely held staples firmly to the tickets.

Other objects and advantages of the invention will appear hereinafter.

A preferred embodiment of the invention selected for purposes of illustration is shown in the accompanying drawings, in which,

Figure 1 is a plan view.

Figure 2 is a side elevation, partly in section.

Figure 3 is a similar view showing the parts in clinching position.

Figure 4 is a fragmentary plan view, partly in section, showing the pin guide.

Figure 5 is a fragmentary view, partly in section, showing the clinching mechanism, the position of the parts corresponding to that shown in Figure 2.

Figure 6 is a similar view, the position of the parts corresponding to that shown in Figure 3.

Referring to the drawings, the clinching mechanism is illustrated as embodied in a marking machine of the general type disclosed in Laencher Patent No. 1,837,450, to which reference may be had for a description of suitable feed mechanism, printing and inking mechanism, etc.

In such machines the main drive shaft 22 carries a feed cam 68 which operates a lever 57 to reciprocate the feed pawl 37. The feed pawl engages the slits formed between successive tickets and advances the strip intermittently, one ticket length at a time.

Mounted on the main drive shaft 22 of the machine are two cams 1 and 2, the cam 1 being utilized to operate a presser foot or clamp 3, and

the cam 2 being utilized to operate the clinching mechanism, designated generally by numeral 4.

The presser foot 3 is carried on a plunger 5 which is mounted to slide in housing 6. The other end of the plunger carries a head 7 which engages the forked arm 8 of a bell crank pivoted at 9, the other arm 10 being provided with a roller 11 which rides on the cam 1. A spring 12 mounted in the housing 6 and surrounding the plunger 5 urges the presser foot and plunger downward, holding the head 7 in engagement with the lever arm 8, and holding the roller 11 against the cam.

The clinching mechanism comprises a housing 15 having a pair of diagonally disposed guideways 16, 16' therein which receive and guide the clincher members 17, 17'. The said clincher members are actuated by plunger 18 which slides in vertical guideway 19, the plunger being provided with a flange 20 which engages slots 21, 21' in the lower ends of the clincher members.

Mounted in the plunger 18 is an anvil 23 which engages the under side of the ticket being clinched and serves as a surface against which the clincher members work while bending the pins to clinched position. The said anvil is spring-pressed, the spring 24 being carried in the plunger 18.

The lower end of the plunger 18 is slotted to receive the forked end of lever 25 by which it is actuated. Lever 25 is pivoted at 26 and carries a roller 27 which engages the cam 2.

As set forth in the aforesaid Marsh application, the loosely held, unclinched staples may be extended in a plane parallel to the plane of the ticket, in order that the ticket strip may be wound into a roll of closely spaced convolutions. Accordingly, it is desirable that the staples be moved to a position perpendicular to the plane of the tickets before being operated upon by the clinching mechanism. In the machine illustrated a guide plate 28 is provided for this purpose having an inclined surface which engages the pins as the strip is fed forward by the feeding mechanism, and guides them into the slot 29 between the parallel plates 30, 30'.

As shown, the housing 6 and the housing 15 may be secured to or formed integrally with a frame 31 which also supports the pivots 9 and 26. The said frame may be attached to the machine casing 32 in any suitable manner.

In the operation of the machine, the operation of the clinching mechanism is timed, of course, to occur between successive feeding movements of the feed mechanism while the ticket strip is sta-

tionary. The presser foot descends first, to clamp the ticket firmly against the upper surfaces of the plates 30, 30'. Then the plunger 18 rises, bringing the anvil against the under surface of the ticket between the pins. Immediately thereafter continued upward movement of the plunger 18 causes the clincher members 11, 17' to engage the pins to bend them from the position shown in Figure 5 to the position shown in Figure 6, in which position they are tightly clinched against the ticket.

It will be understood that the invention may be variously modified and embodied within the scope of the subjoined claims.

I claim as my invention:

1. In a marking machine for feeding and printing pin tickets carrying unclinched, loosely held staples having a pair of parallel pins, a pair of spaced parallel plates arranged perpendicular to the face of said tickets and having a slot therebetween, means to feed said tickets intermittently lengthwise of said slot with said parallel pins extending into the slot, means to guide said pins into the slot between said plates as said tickets are fed forward, and means operating vertically within the slot between said plates to bend said staples at points closely adjacent said ticket to clinch said staples firmly to said ticket, said pins remaining parallel and extending in a direction substantially perpendicular to said ticket.

2. In a marking machine for feeding and printing pin tickets carrying unclinched, loosely held staples having a pair of parallel pins, a pair of spaced parallel plates arranged perpendicular to the face of said tickets and having a slot therebetween, means to feed said tickets intermittently lengthwise of said slot with said parallel pins extending into the slot, means to guide said pins into the slot between said plates as said tickets are fed forward, and means operating within the slot between said plates to bend said staples at points closely adjacent said ticket to clinch said staples firmly to said ticket, said clinching means comprising an anvil operating vertically between said pins and oppositely disposed clincher members working vertically outside said pins, said anvil serving to restrain said pins in one direction and said plates serving to restrain said pins in other directions during the clinching operation, whereby said clinched pins remain parallel and extend in a direction substantially perpendicular to said ticket.

in other directions during the clinching operation, whereby said clinched pins remain parallel and extend in a direction substantially perpendicular to said ticket.

5 3. In a marking machine for feeding and printing pin tickets carrying unclinched, loosely held staples having a pair of parallel pins, a pair of spaced parallel plates arranged perpendicular to the face of said tickets and having a slot therebetween, means to feed said tickets intermittently lengthwise of said slot with said parallel pins extending into the slot, and means operating within the slot between said plates to bend said staples at points closely adjacent said ticket to clinch said staples firmly to said ticket, said clinching means comprising an anvil operating vertically between said pins and oppositely disposed clincher members working vertically outside said pins, said anvil serving to restrain said pins in one direction and said plates serving to restrain said pins in other directions during the clinching operation, whereby said clinched pins remain parallel and extend in a direction substantially perpendicular to said ticket.

20 4. In a marking machine for feeding and printing pin tickets carrying unclinched, loosely held staples having a pair of parallel pins, a pair of spaced parallel plates arranged perpendicular to the face of said tickets and having a slot therebetween, means to feed said tickets intermittently lengthwise of said slot with said parallel pins extending into the slot, means to engage the front face of the ticket to hold the same above said plates, and means operating within the slot 30 between said plates to bend said staples at points closely adjacent said ticket to clinch said staples firmly to said ticket, said clinching means comprising an anvil operating vertically between said pins and oppositely disposed clincher members working vertically against said ticket engaging means and outside said pins, said anvil serving to restrain said pins in one direction and said plates serving to restrain said pins in other directions during the clinching operation, whereby said clinched pins remain parallel and extend in a direction substantially perpendicular to said ticket.

JOSEPH WEIMONT.
